A. H. Graton,
Hook Skirt.

No. 90,797.

Patented Nov. 10, 1869.

Witnesses:
John Clark
Dwight D. Dickey

Inventor:
Mr. A. H. Graton

PER

M. M. L.

Attorneys.

United States Patent Office.

A. H. GRATON, OF LAWRENCE, KANSAS.

Letters Patent No. 96,797, dated November 16, 1869.

IMPROVEMENT IN DRESS AND SKIRT-PROTECTORS.

The Schedule referred to in these Letters Patent and making part of the same.

To all whom it may concern:

Be it known that I, Mrs. A. H. GRATON, of Lawrence, in the county of Douglas, and State of Kansas, have invented a new and improved Dress-Protector; and I do hereby declare that the following is a full, clear, and exact description thereof, which will enable others skilled in the art to make and use the same, reference being had to the accompanying drawing, forming part of this specification.

My invention is an improvement in skirt-protectors; and

The improvement consists in the construction, and in the mode of attaching the skirt-protector to the person of the wearer, as hereinafter set forth.

In the drawings, my invention is represented as applied to the person of the wearer, part being broken away, to show the distending-ring and the arrangement of the skirts.

A represents the exterior, and B, the interior part of an annular sack, formed by sewing the lower edge of the interior part to the part A, a short distance above the lower edge of the latter, and providing it with outer suspending-straps C, and interior straps D, the former connecting with a waist-belt, E, and the latter hooking on to one of the lower hoops of the hoop-skirt.

The bottoms of the skirts are stowed in this sack, and thus protected from damage by the mud and water, when walking.

To prevent the accumulated weight of the skirts causing the "protector" to press inward against the ankles of the person, at one or more points, thus rendering easy or graceful movement impossible, besides soiling the bottoms of the hose or under-skirts, I have provided a ring, a, for distending the protector, and causing it to assume and retain the form of a circle.

I am aware that the elements of my combination, separately considered, are found in existing patents, but I claim nothing therein shown.

What I consider as my invention, and desire to protect by Letters Patent, is—

The dress-protector herein described, when composed of the parts A B, united as shown, provided with a distending-ring, a, and adapted to be attached to the person of the wearer by the outer straps C and waist-belt E, and the short interior straps D, and their hooks e, by which they are attached to the lower portion of the skirt, all as hereinbefore shown and described.

MRS. A. H. GRATON.

Witnesses:

ROBT. R. DUNBAR,
MRS. MARY HART.